UNITED STATES PATENT OFFICE.

MORRIS W. POOL, OF NEW YORK, N. Y., ASSIGNOR TO THE MONARCH TYPEWRITER COMPANY, OF SYRACUSE, NEW YORK, A CORPORATION OF NEW YORK.

TYPE-WRITING MACHINE.

No. 806,834.

Specification of Letters Patent.

Patented Dec. 12, 1905.

Application filed August 20, 1904. Serial No. 221,518.

To all whom it may concern:

Be it known that I, MORRIS W. POOL, a citizen of the United States, and a resident of the borough of Brooklyn, city of New York, in the county of Kings and State of New York, have invented certain new and useful Improvements in Type-Writing Machines, of which the following is a specification.

This invention relates to type-writing machines, and has for its main objects to provide a support for the paper on which erasures may conveniently be made and to provide a mounting for the paper guiding and holding means.

15 My invention consists in certain features of construction and combinations of devices, all as will be hereinafter more fully described, and particularly pointed out in the concluding claims.

20 In the accompanying drawings, Figure 1 is a top plan view of the platen and the platen-frame of a type-writing machine, showing my invention embodied therein, certain parts being omitted for the sake of clearness. Fig. 2 is a sectional side elevation taken on the line *x x* of Fig. 1. Fig. 3 is an enlarged perspective view of the supporting-arm of the paper-finger. Fig. 4 is a view similar to Fig. 1, showing a modification of the invention. 25 Fig. 5 is a view taken on the line *y y* of Fig. 4, various parts being omitted. Fig. 6 is an enlarged perspective view of the paper-finger shown in Figs. 4 and 5.

Considering first Figs. 1 to 3, inclusive, 1 is the top plate of the machine, and 2 one of the posts for the guiding and supporting rails 3 for the platen-carriage 4. The grooved back bar 5 of the platen-carriage co-operates with the rails 3 through roller-bearings, and 5 the side bars 6 and 7 serve to support the platen 8. The paper, which is represented by the dotted line 9 in Fig. 2, is fed around the platen in a manner well understood, passing into the machine over the paper-table 10 and 45 paper-apron 11 in rear of the platen. The side bars 6 and 7 are formed with standards or lugs 12 and 13, which serve to support a plate-like erasing-shelf 14, the ends of which terminate in short rod-like portions 15. The 50 rod-like portions are preferably constructed of separate pieces of metal, which after being properly formed are suitably attached, as

by soldering, to the erasing shelf or plate 14. The outer ends of the rod-like portions are formed with holes which are tapped to receive 55 the headed screws 16, the latter passing through perforations in the lugs 12 and 13 and being screwed tightly into the ends of the rod-like portions 15. The erasing-plate is thus fixedly secured in position, a tongue-and-groove connection with the lugs 12 and 13 preventing rotation or lateral displacement. Mounted upon the erasing-plate are the marginal paper-fingers 17, each of which is composed of a supporting portion 18 and a holding 60 and guiding portion 19. The supporting portion 18 preferably comprises, first, a guide-block 20, which has milled or otherwise suitably formed longitudinally of its upper face a dovetailed groove or mortise 21; second, a forwardly-projecting arm 22, which terminates in bearing-eyes 23, and, third, a thumb-piece 24. As herein shown, the bearing-block 20 is constructed of a solid block of metal, and the forwardly-projecting arm 22 is made of a thin 70 metal strip, which is punched or cut and afterward so bent or shaped as to form the bearing-eyes 23 and the thumb-piece 24. The arm 22, having the bearing-eyes and thumb-piece integral therewith, is suitably attached, 75 as by soldering, to the bearing-block 20. Mounted in the bearing-eyes 23 is a short rod 25, the inner end 26 of which projects sufficiently beyond the adjacent bearing-eye to permit the said rod 25 to be pinned to or 80 otherwise suitably connected with the short offset arm 27 of the guiding and holding portion 19 of the paper-finger. A coiled spring 28 surrounds that portion of the rod 25 which is between the bearing-eyes 23 and presses 85 the guiding and holding portion toward the platen, the rod 25 serving as a pivot when the paper-finger is mounted in position on the machine. This latter operation is preferably accomplished by forming the under side of 90 the erasing shelf or plate 14 about midway its width with a longitudinal dovetail or tongue, which is shaped to conform to the dovetailed groove 21 of the bearing-block, the latter being mounted to slide longitudinally of the 95 erasing-plate upon the said dovetail 29. As best appears in Fig. 2, the erasing-plate is fixedly supported in proximity to the top of the platen and slightly to the rear of its axis,

- the blade or plate-like portion extending downwardly and forwardly in the general direction of the delivery ends of the holding and guiding portions 19 of the paper-fingers.
- 5 The latter are slidably attached to the under side of the erasing-plate and project forwardly beneath the latter and between it and the upper surface of the platen. This affords a construction of neat and simple appearance, the
- 10 connection between the erasing-plate and the paper-finger being concealed from view and only the forward part of the latter being visible from the operator's position. Furthermore, by this construction the entire top
- 15 surface of the erasing-plate is at all times left free and unobstructed. The offset arm 27 of the guiding or feeding portion 19 enables the latter to be offset inwardly or toward the center of the machine from the support or
- 20 slide 18. By this construction the guiding or feeding portions of the paper-feeding devices may be arranged far enough apart to engage the paper near its side edges, while by reason of the offsets 27 the slides 18 will at
- 25 the same time be separated far enough to enable the full width of the paper to pass between them. The top or leading edge of the paper will, therefore, after passing upward out of engagement with the guiding or feeding means pass over the erasing-plate, the top surface whereof, as previously stated, is always free and clear for making erasures.
- The invention is illustrated as applied to the Monarch type-writing machine. It is to be understood, however, that the said invention is not limited to the particular construction hitherto described, but that it may be adapted to other forms of writing-machines and that various changes of construction and
- 35 arrangements of parts may be effected within its scope. The erasing-plate, for example, may itself be spring-mounted in the platen-frame, while the coiled spring 28, which serves to press the guiding and holding portion of
- 40 the paper-finger toward the platen, may be dispensed with and the said guiding and holding portion may be rigidly connected with its supporting-arm. Such a modification is illustrated in Figs. 4 to 6, inclusive.
- 45 In the modified construction the erasing-plate 14 is provided with end portions 30, which are perforated longitudinally to permit of the passage of headed screws 31, which are screwed into the lugs 12 and 13 and which
- 50 pass loosely through the end portions 30. The said screws 31 act as pintles for the erasing-plate, the forward edge of which is pressed toward the surface of the platen by a spring 32, which is coiled about the right-hand pin-
- 55 tle 31 and one end of which bears against the erasing-plate, while the other end is held in or upon the lug 13. The under side of the erasing-plate is provided with a dovetail or tongue 33, which extends longitudinally of
- 60 the erasing-plate and upon which the paper-

fingers 34 are mounted. Each of the paper-fingers comprises a supporting-arm 35 and a guiding and holding part 36, which is rigidly secured to the supporting-arm. The supporting arm or portion is formed with a dovetailed groove 37, by means of which the paper-finger is mounted upon the dovetail or tongue 33, and thus secured to the erasing-plate.

It will be noted that the general arrangement of the parts is similar to that of the first-described construction and that the paper-finger may be moved from side to side of the machine beneath the erasing-plate and between it and the platen by means of a thumb-piece 38, formed on the paper-finger forward of the erasing-plate. The paper-finger spring 28 of the first-described construction is, however, dispensed with in the modified form, the paper-finger in the latter case having transmitted to it the pressure of the spring-mounted erasing-plate.

Other changes of form, construction, and arrangements of parts may be made without departing from the gist of my invention.

What I claim as new, and desire to secure by Letters Patent, is—

1. In a type-writing machine, the combination of a platen, an erasing-plate, and means for guiding the paper, said means projecting forwardly from beneath said erasing-plate, said means being in part between said platen and said erasing-plate.

2. In a type-writing machine, the combination of a platen, an erasing-plate, and means for guiding the paper, said means projecting forwardly from beneath said erasing-plate and being movable longitudinally of the platen beneath said erasing-plate.

3. In a type-writing machine, the combination of a platen, an erasing-plate, and means for guiding the paper, said means projecting forwardly from beneath said erasing-plate and being secured to said erasing-plate.

4. In a type-writing machine, the combination of a platen, an erasing-plate, and means for holding and guiding the paper, said means projecting forwardly from beneath said erasing-plate and being movable longitudinally of the platen beneath said erasing-plate.

5. In a type-writing machine, the combination of a platen, an erasing-plate, and a paper-finger, said paper-finger being mounted upon said erasing-plate and projecting forwardly from beneath said erasing-plate.

6. In a type-writing machine, the combination of a platen, an erasing-plate, and a paper-finger comprising a supporting-arm and a guiding part secured to said supporting-arm, said supporting-arm projecting forwardly beneath the erasing-plate and being in part between said erasing-plate and said platen.

7. In a type-writing machine, the combination of a platen, an erasing-plate and a paper-finger comprising a supporting-arm and a

spring-pressed guiding part pivotally mounted upon said supporting-arm, said supporting-arm projecting forwardly beneath said erasing-plate and between the platen and said erasing-plate.

8. In a type-writing machine, the combination of a platen, an erasing-plate and a paper-finger comprising a supporting-arm and a guide, said paper-finger being arranged between said platen and said erasing-plate.

9. In a type-writing machine, the combination of a platen, an erasing-plate and a paper-finger mounted upon said erasing-plate and between it and the platen, said paper-finger comprising a supporting part and a guiding part pivoted upon said supporting part and spring-pressed toward the platen.

10. In a type-writing machine, the combination of a platen, an erasing-plate formed with a dovetail longitudinally of its under side, and a paper-finger formed with a dovetailed groove or mortise and mounted to slide upon said erasing-plate.

11. In a type-writing machine, the combination of a platen, an erasing-plate and a paper-finger mounted upon and adapted to slide longitudinally of said erasing-plate and being so arranged as to leave the entire top surface of the erasing-plate at all times free and unobstructed.

12. In a type-writing machine, the combination of a platen, an erasing-plate, a slide mounted on the under side of said plate, and paper

guiding or feeding means attached to said slide.

13. In a type-writing machine, the combination of a platen, an erasing-plate, and adjustable paper-guides supported from the under side of said erasing-plate, whereby the paper feeds over the plate and the top of the plate is at all times free and clear for the making of erasures.

14. In a type-writing machine, the combination of a platen, an erasing-plate, and adjustable paper-feeding means supported from the under side of said plate.

15. In a type-writing machine, the combination of a platen, an erasing-plate, offset paper-feeding devices, and supports therefor adjustably mounted on the under side of said plate.

16. In a front-strike type-writing machine, the combination of a platen, an erasing-plate mounted above said platen, and a paper-finger mounted on the under side of said erasing-plate and extending in front of the platen, said paper-finger being slidable longitudinally of the platen.

Signed at the borough of Manhattan, city of New York, in the county of New York and State of New York, this 19th day of August, 60
